(57) **CLAIM**

The ornamental design for a drop foot prevention device, as shown and described.

DESCRIPTION

FIG. 1 is a top, right side, perspective view of a drop foot prevention device showing my new design;
FIG. 2 is a top perspective view thereof; and,
FIG. 3 is another top, right side, perspective view thereof, as worn by a person wearing a sandal shown in broken lines. The broken lines shown in FIG. 3 illustrate environmental subject matter and form no part of the claimed design.

1 Claim, 3 Drawing Sheets

FIG. 1

FIG. 2

FIG. 3
